UNITED STATES PATENT OFFICE.

ALBERT E. HATHAWAY, OF NORTH ATTLEBORO, MASSACHUSETTS,
ASSIGNOR TO R. BLACKINTON & CO., OF NORTH ATTLEBORO,
MASSACHUSETTS, A FIRM.

DESIGN FOR A BACK OF A BRUSH.

No. 38,230.

Specification for Design.

Patented Sept. 11, 1906.

Application filed July 31, 1906. Serial No. 328,622. Term of patent 7 years.

To all whom it may concern:

Be it known that I, ALBERT E. HATHAWAY, a citizen of the United States, residing at North Attleboro, in the county of Bristol and State of Massachusetts, have invented a new, original, and ornamental Design for the Back of a Brush, reference being had to the accompanying drawing.

The figure in the drawing is the back view of a brush, showing my design.

I claim—

The ornamental design for the back of a brush, as shown.

ALBERT E. HATHAWAY.

Witnesses:

ADA E. HAGERTY,
J. A. MILLER.
